US0D1013100S

(12) **United States Design Patent** (10) **Patent No.:** **US D1,013,100 S**
(45) **Date of Patent:** **** Jan. 30, 2024**

(54) **NOZZLE**

(71) Applicant: **Danfoss A/S**, Nordborg (DK)

(72) Inventors: **Steen Gaardsted Kristensen**, Nordborg (DK); **Preben Nørskov**, Nordborg (DK); **Leif Boesen Bonnerup**, Nordborg (DK)

(73) Assignee: **Danfoss A/S**, Nordborg (DK)

(**) Term: **15 Years**

(21) Appl. No.: **29/808,831**

(22) Filed: **Sep. 23, 2021**

(30) **Foreign Application Priority Data**

Mar. 24, 2021 (EM) 008473102

(51) **LOC (14) Cl.** **23-01**

(52) **U.S. Cl.**

USPC **D23/213**

(58) **Field of Classification Search**

USPC D23/213, 214, 222, 228, 229

CPC B05B 1/10; B05B 1/3006; F16K 15/044
